UNITED STATES PATENT OFFICE

2,669,005

SINGLE SPINDLE AUTOMATIC LATHE

Carroll E. Miller, Windsor, Vt., assignor to Cone
Automatic Machine Company Inc., Windsor,
Vt., a corporation of Vermont

Application November 3, 1948, Serial No. 58,074

22 Claims. (Cl. 29—43)

1

This invention relates to automatic lathes of the single work spindle type in connection with which there are a plurality of tool-holders which are brought into operation successively, these tool-holders being carried by a turret which is periodically indexed to bring the holders successively into operative relation to work carried by the work spindle.

One of the objects of this invention is to provide for selective and easy elimination of operation of tool-holders where less than all of the stations of the turret are desired to complete the tooling operations.

A further object is to provide for varying the throw of the tool-holders without requiring the substitution of different actuating cams therefor.

A further object is to improve the mechanism for producing the feed, both fast or slow working, and the fast retraction of the tool-holders.

Still another object is to provide simple means by which one or more tools may be caused to undercut and without requiring special tool attachments for that purpose. This object is attained by causing the tool-holder turret to rock during the cutting operation, and this also makes possible taper cutting of the work either externally or internally.

Further objects and advantages will appear from a description of an embodiment thereof shown in the accompanying drawings in which

Figure 1 is a longitudinal vertical sectional view through the machine on line 1—1 of Figure 2.

Figure 2 is a left hand end elevation of the machine.

Figure 3 is a fragmentary view similar to a portion of Figure 1, but to a larger scale and with parts broken away and in section.

Figure 4 is a right hand end elevation of the parts shown in Figure 3, the cover being removed.

Figure 5 is a detail sectional view on line 5—5 of Figure 4.

Figure 6 is a detail sectional view on line 6—6 of Figure 3 and to a larger scale on line 6—6 of Figure 1.

Figure 7 is a detail sectional view on line 7—7 of Figure 8.

Figures 7a and 7b are detail sectional views on lines 7a—7a and 7b—7b of Figure 7.

Figure 8 is a view to a larger scale of parts shown in Figure 4 at the end of an indexing.

Figures 9 and 10 are views similar to Figure 8 but with parts of the indexing and feed control mechanisms in different positions.

Figures 11 to 15 are fragmentary end elevational views showing certain indexing and control parts in different positions.

2

Figure 16 is an exploded perspective view of the tool carrying turret and actuating mechanism for the tool slides.

Figures 17, 21, 24, 27 and 30 are top plan views of the indexing plate on the tool slide in various adjusted positions.

Figures 18 to 20, 22 and 23, 25 and 26, 28 and 29, 31 and 32, respectively, are fragmentary side elevations of the actuating cam with actuating elements positioned to correspond with the positions of the indexing plate in the next previously numbered figures for definite lengths of feed.

Figure 33 is a fragmentary developed peripheral view of the cam actuating drum with cam followers secured thereto.

Figures 34 to 37, inclusive, are diagrammatic views of the tool feed mechanism showing the relative extents of fast and slow feed for one angular adjustment of the modifying block.

Figures 38 and 39 are diagrammatic views similar to Figures 35 and 37, respectively, but showing a different angular adjustment of the modifying block.

Figures 40 and 41 are views similar to Figures 35 and 37, respectively, but showing the effect of a third different angular adjustment of the modifying member.

Figure 42 is a view similar to Figure 38 and in dotted lines similar to Figure 41, but showing the effects of a different adjustment of the cam follower in the cam actuating mechanism.

As best shown in Figures 1, 2 and 3, the machine comprises a bed 1 having at opposite ends the vertically extending columns 2 and 3 joined at their upper ends by a horizontal casing 4, this casing containing, extending longitudinally thereof, a controlling cam shaft 5. The column 2 has journaled for rotation therein a work-carrying spindle 6, a work piece 7 being shown carried thereby in Figure 1. Beneath the work spindle, and extending through the space between the columns 2 and 3 and into each of these columns, is a shaft 10 which carries thereon a tool-carrying turret 11.

As shown best in Figures 6 and 16, this tool-carrying turret 11 is polygonal in outline, having five sides, on each of which may be mounted a tool slide 15. One of these slides, as shown in Figure 1, may carry a drill or other tool as shown at 16 and the several tools may be brought successively into operative relation to the work 17 by indexing the turret 11 about the axis of the shaft 10. The cam shaft 5 which controls many of the operations of the machine is rotated by any suitable means, as shown such means comprising a worm wheel 20 carried by the cam shaft 5 and driven by a worm 21 on a cross shaft 22. The cam shaft 5 is driven at a relatively fast

idle speed and at a relatively slow working speed, the working speed being effective during the time that any one of the tools is operating upon the work carried by the spindle. Details of mechanism for so driving the cam shaft may be as shown in my United States Letters Patent No. 2,506,515 granted May 2, 1950, for Automatic Lathe or Screw Machine. Means for feeding a work piece through the spindle 6, including a feed cam 23 carried by the shaft 5, and other cams 24, 25, and a series of cams on an elongated cam drum 26 carried by the shaft 5 may also be employed for controlling various operations of the machine in accordance with usual practice.

This invention is concerned primarily with the actuation and control of the tools carried by the turret and the indexing of the turret.

The indexing of the turret is produced by rotation of the cam shaft 5 through a Geneva wheel 30 having five Geneva slots 31 corresponding to the five faces of the turret, this Geneva wheel being turned intermittently by the action of the Geneva arm 32 keyed to a jack shaft 33 positioned beneath the cam shaft 5 and journaled in the end walls of the column 3. The Geneva wheel 31 is secured to a quill 34 journaled on the shaft 10 and having at one end a bearing flange 35 (see Figure 3) journaled in the inner wall 36 of the column 3. The opposite end of the quill 34 has a bearing flange member 37 journaled in the outer wall 38 of the column 3. The inner bearing flange 35 is secured to the outer end of the turret 11 as by screws 39. The shaft 33 is driven at intervals by power, this being accomplished through a worm wheel 40 secured thereto and with which cooperates a worm 41 on a horizontal shaft 42. This horizontal shaft 42 may be rotated by power through a clutch at 43, which when closed, couples to the shaft 42 a sprocket wheel 44 about which passes a drive chain 45 passing about a drive sprocket wheel 46 fixed to the shaft 47 of a motor 48 (see Figure 6).

The shaft 42 at its other end is connected through a similar clutch 50 to a normally stationary drum 51. The drum 51 has a worm 52 with which meshes a worm wheel 53 on a shaft 54. The stop 55 is carried by this worm wheel 53 which normally engages one side of the worm 52, thus locking the worm wheel against motion in normal driving direction so that the clutch 50 acts as a brake to stop the rotation of the shaft 42 when the clutch 50 is closed. It does not, however, prevent reverse rotation applied to the outer end of the polygonal extension of the drum 51 to which the normally disconnected hand wheel 56 may be applied, reverse rotation of this drum retracting the stop 55. Such retraction moves a limit switch-actuated wedge 57 out of a notch in a disk 58 carried by the shaft 54, making it impossible to start the machine by power until the drum 51 has been returned to braking angular position. This arrangement is similar to that shown in my Patent No. 2,506,515 granted May 2, 1950.

The means for actuating the clutches 43 and 50 is, however, quite different in the present application. The two clutches 43 and 50 are shown as connected by a drag bar 60 which has lugs 59 which engage the lower forked extremities 61 and 62 of a pair of bell crank levers 63 and 64. The adjacent ends of these bell crank levers 63 and 64 have follower rolls 65 and 66, respectively, positioned to be engaged by a cam 70 carried by a rock shaft 71, there being five of these rock shafts 71 spaced angularly around the axis of the shaft 10 and parallel therewith, one

5 for each of the indexed positions of the turret, and each being journaled through the flange 37 and the Geneva wheel 30. The indexing control is thus effected through mechanism specific for each indexed position or station of the turret. Each of these shafts 71 carries a dog 72, the dogs of the several shafts being offset axially so that each one lies in the plane of a corresponding lobe 73 on a ring 74, which may be clamped in adjusted angular position to the outer face of a hub or drum 75 journaled on the shaft 33 and driven independently of the shaft 33 by chain and sprocket drive from the main cam shaft 5. Each of the rings 74 is formed split, the two split ends being adapted to be brought toward each other to clamp the ring in adjusted position by tightening a bolt 76 extending through one of the end portions and threaded into the other, as shown best in Figure 8.

20 Each of the five rock shafts 71 has keyed thereto a hub 78 carrying a dog 80 and all of these dogs 80 are in the plane of a cam 81 on the indexing arm 32 carried on the jack shaft 33. On the outer end of each rock shaft 71 is a crank arm 85 provided with a pin 86 connected by a spring 87 to a pin 88 on a bracket 89 secured to the outer face of the Geneva wheel 30 and in which the outer end of the corresponding rock shaft 71 is journaled. Each crank arm 85 has a pair of flat sides, either of which may be pulled toward a flat face 90 on the bracket 89 depending upon the angular relation of the crank arm 85. When one of the shafts 71 is turned to the angular position shown in Figure 15 with the crank arm 85 thrown to the left of center, the dogs 72 and 80 and the cam 70 are in the inoperative position shown and they are ineffective upon the indexing mechanism. In the position of the shaft 71 shown in Figures 4, 7, 8 and 11 to 14, inclusive, with a crank arm 85 to the right of center, the corresponding shaft 71 is in operative angular position.

25 In the position of the parts before an indexing action is to take place, the cam follower 66 is elevated and the follower 65 is depressed in the position shown in Figures 7b and 12 and the cam 70 on the rock shaft 71, which is then immediately below the jack shaft 33, extends vertically as shown. A low portion 82 of the cam 81 engages the dog 80, as shown in Figures 7a and 12. The shaft 42 is thus disconnected from the motor drive, the clutch 43 being open and the clutch 50 closed. As the control shaft 5 continues to rotate, which also rotates the drum 75, this rotation being now in the slow speed angular portion, the lobe 73 which happens to be in the plane of the dog 72 of the shaft 71 which is in uppermost position, contacts this dog 72 and rocks it to the left, which, in turn, rocks the cam 70 into the left dotted line position shown in Figure 7b. The inclined upper end of the cam 70 then presses the cam follower 65 upwardly and allows the follower 66 to drop as in Figure 13, this shifting the drag bar 60 to the right and closing the clutch 43, which starts the rotation of the shaft 42 by the action of the motor 48. The rotation of the jack shaft 33 is thus begun. This causes the indexing arm 32 to start its rotation from the position shown in Figure 13. At the time its follower is in position to enter one of the Geneva slots 31 at 30 Figure 9, the indexing action commences, turning the Geneva wheel and the turret by one-fifth of a rotation. Before the indexing action has commenced, however, the high portion of the cam 81 engages the dog 80 and holds the rock shaft 71 which is then in operative position, in the an-

5

angular position shown in left hand dotted lines in Figures 7a and 7b, and in Figure 14, against the action of the spring 87 which tends to throw the rock shaft 71 in the opposite direction back to the right hand dotted line position of Figure 7b, and this shaft 71 is still in this angular position when it is moved out from beneath the cam roll 65 (Figure 10) by the indexing motion of the Geneva wheel and turret, which carries it out of operative position and brings the next rock shaft 71 into position. This succeeding rock shaft, being free to be acted upon by its spring 87 has the right hand side of its arm 72 in engagement with the face 90 and its cam 70 in the right hand dotted position of Figure 7b and in Figure 11. When the low portion 82 of the cam 81 comes into position to engage the dog 80 of this next rock shaft 71, it rocks it to the full line position of Figure 7a. This brings the cam 70 to the full line position of Figure 7b which lifts the follower roll 66 and stops the rotation of the jack shaft. The Geneva arm is then in the angular position of Figure 12 and the jack shaft is idle until the next lobe 73 comes into action to rock the shaft 71 further counterclockwise and start the next indexing action. During this rotation of the control shaft 5 and the power rotation of the jack shaft 33, certain idle movements of a tool carrier on the turret are also effected as will later appear.

The tool-carrying turret between indexing motions is locked in position, but means may be provided by which the locking means is actuated to rock the turret about its indexing axis during the operation of tools carried by the turret on work carried by the spindle. The locking means, as shown, comprises a lever 100 having a locking finger 101 pivoted to its lower end and slidable over the pivotally mounted block 1011 and which may be engaged in any one of a series of lock plates 102 carried by the Geneva wheel, each having a recess 103 in its outer edge for the reception of the locking finger. The lower end of the lever 100 is forked and engages a stationary guide fin 1012. This locking lever 100 is shown as fulcrumed at its upper end as at 104 and intermediate its ends it is provided with a lateral extension 105 carrying a cam follower roll 106 which may be engaged by a cam 107 carried by the Geneva arm 32 to be pressed to the right, as viewed in Figures 4, 8, 9 and 10, against the action of a multiple leaf spring 108, to retract the locking finger 101 from one of the recesses 103 in the Geneva wheel. This causes the lock to be released for the indexing operation, at the end of which time the cam 107 leaves the follower 106 and allows the locking finger 101 to be sprung into the next recess 103 of the locking plate which comes opposite thereto. The lock is shown in released position in Figure 10.

As before noted, means is provided for moving the locking device while it is in engagement with the turret to thereby rock the turret during a tooling operation. By doing this, undercutting of the work may be accomplished since this moves the tool laterally with respect to the work. As shown best in Figures 5 and 10, the fulcrum 104 for the locking lever 100 is mounted for vertical motion on a slide 110 which is mounted between vertical guide members 111. The upper end of the lever 100 is forked, as shown best in Figure 5, and on the fulcrum pin 104 between the forks is mounted a block 112 connected through a pair of links 113 pivoted thereto to an arm 114 of a bell crank lever 115 fulcrumed on a station-

6

ary pivot 116 and having its upwardly extending arm provided with a cam follower roll 117 in the path of motion of a cam 118 on a cam drum 119 carried at the end of the shaft 5. When this 5 cam 118 rocks the bell crank lever 115 to lift its arm 114, it lifts the lever 100 with the locking finger 101 while it is in locking engagement with the Geneva wheel which thus acts to rock the Geneva wheel. A second cam (not shown) on the cam drum 119 may be employed to return the fulcrum of the indexing arm to its normal position. The lower limit of motion of the slide 112 is defined by a stop screw 120 carried by a lug 121 secured to the machine frame as by a threaded shank and a nut at 122 (see Figure 5). This stop screw 120 determines the normal locking angular position of the turret, and where no undercutting is desired, it defines the locked angular positions of the turret at its various stations.

Besides controlling the indexing of the turret, the shaft 33 also has an important function with relation to the motion of the tools on the various tool carriers. Referring particularly to Figures 1, 3, 7 and 34 to 42, it will be noted that this jack shaft 33 has a cam 130 fixed to rotate therewith and provided with a peripheral cam groove 131 therein. This cam groove has a portion at the right which is perpendicular to the shaft 33 and also has a portion to the left which communicates with the right hand end portion through the inclined portions 132 and 133. Riding in this cam groove 131 is a follower 135 carried by a slide 136. This slide is mounted on suitable ways 35 extending lengthwise of the machine so as to move parallel to the axis of the control shaft 5 and also to the jack shaft 33. On this slide 136 a lever 138 is fulcrumed at 137. The upper end of this lever is connected through an adjustable 40 pivoted link 140 to a second slide 141 which is mounted to slide on a stationary guide bar 142 and which has a forwardly extending fork 143 in sliding relation to the control shaft 5 (see particularly Figures 6 and 16). This slide 141 is provided with a sloping segmental cam face 144 adapted to be contacted at suitable times by cam followers such as 145 which are selectively positionable around the periphery of a drum 146 keyed to the control shaft 5. The 45 right hand limiting position for the slide 141 is determined by contact of this slide with a suitable stop abutment 148. The left hand limit of sliding motion is determined by a roll 149 projecting from the periphery of the drum 146 at one portion of its periphery (see Figures 18, 19, 33, 34, and 35).

The lower end of the lever 138 has a follower roll 150 which may engage within a notch 151 in any of the slides 152 mounted for axial sliding motion parallel to the axis of the shaft 10 and arranged angularly spaced around the periphery of the turret. The forward limit of motion of each slide may be determined by stop nuts 153 (Figure 7) on threaded rods 154. Since as shown, the turret has five indexing positions or stations, it has provision for mounting five slides 152 equally angularly spaced around the periphery of the turret, but as will later more fully appear such slides may be omitted from one or more of these positions when the tooling does not require the entire five to be used.

When the slides 152 are in fully retracted positions, the slots 151 therein are so positioned lengthwise of the turret that they may be brought 70 serially into cooperative relation to the cam roll

150 whenever this cam roll 150 is in its fully retracted position. When it is in such position the slide 141 is at its right hand limit of motion up against the stop as shown in Figure 34 and the cam follower 135 is in the right hand portion of the cam groove 131. This is the position of these parts when indexing is occurring.

After the indexing has been completed and while the jack shaft 33 is still being rotated, the cam 130 is rotated to a position to move the fulcrum 135 to the left into its left hand portion 132 in fast speed. This brings the tool slide 15 forwardly in fast speed until the tool carried thereby, as will later appear, approaches contact with the work, this being the position in Figures 35, 38, 40 and 42. This brings the slide 141 with the edge cam 144 to the left into contact with one of the followers 145 on the drum 146. The motion of the jack shaft 33 stops in this angular position of the cam 130. As the control shaft 5 now turns at low speed the operative follower roll 145 then acting upon the edge cam 144, forces the slide 141 to the right and moves the slide 152 further to the left, this effecting the slow feed of the tool into the work. This takes place until this feed action is at an end when the follower 145 reaches about the high point of the cam edge 144, whereupon the succeeding lobe 73 contacts and rocks the dog 72 of the shaft 71 then in operating position, and starts the rotation of the jack shaft 33. As soon as this occurs the cam 130 rotates to move the follower 135 to the right, withdrawing the tool at fast speed and also pulling the slide 141 back against the stop in position for the indexing to occur, whereupon the succeeding tool slide 152 will be brought into cooperative relation to the cam roll 150 at the lower end of the lever 138.

Means are provided by which the relative extents of fast and slow feed of the tools may be adjusted independently, and as shown, this means comprises the selective positioning of the followers 145 in the drum 146 and also adjustments at the tool slides themselves, as will now be pointed out. The angular position of the cam roll 145 on its drum 146 with which the cam face 144 contacts when this contact is made, determines how much of the length of this cam face will be effective in moving the slide 141 and consequently in swinging the lever 138 to produce the feed motion of the tool. For example, if the slide 141 is moved forwardly toward the drum 146 when the follower 145 which will contact the cam face 144 is toward the upper portion of this cam, substantially the entire length of the cam face 144 is effective in producing the feed motion of the slide 141 and consequently the feed motion imparted to the lever 138. If, however, when the slide 141 starts its forward movement, the cam follower 145 with which it will contact is nearer its lower limit of motion as the drum 146 revolves, a smaller length of the cam face 144 will be traversed by this cam follower and consequently a small amount of the movement of the slide 141 will occur with a consequent smaller amount of swinging motion imparted to the lever 138.

For the purpose of providing for various adjustments of the effective cam roll 145, the drum 146 is shown as provided with a series of holes 160 which are provided for selective reception of the pivot elements 161 on which the follower rolls 145 are journaled, a suitable washer 162 and a nut 163 threaded on the inner end of the shank 161 being employed to secure the cam fol-

lower roll 145 in position. It will also be noted that due to the angular spacing of the various lobes 73 corresponding to the various indexed positions or stations of the turret, the forward motion of the slide 141 is started at different angular positions of the control shaft 5 for the several index stations, and consequently it is possible to employ a different follower roll 145 for each of these stations, only one of these rolls being effective at one time against the cam face 144.

Each of the slides 152 is connected to its respective tool carrier by a similar mechanism. The forward ends of each of the slides 152 is forked at 175 and between the forks is pivoted on a vertical pivot 176, a bar 177. The forward end of the bar 177 is provided on its lower face with a cam follower roll 178 which rides in an angle slot 179 in a guide plate 180 secured to a side face of the turret. This slot 179 from its rear end extends forwardly and to the left for substantially half its length and then it turns to the right for the remainder of its length. Thus the cam roll 178 as it passes lengthwise of this slot is caused to move first to the left and then to the right as it is moved inwardly by inward sliding of its slide 152. On its upper face, it carries, pivoted on a pivot 182, a slide block 183, and this slide block slidably engages in a groove 184 cut across the lower face of a disk 185. This disk 185 is journaled in a cylindrical bearing 189 which extends upwardly from a slide 190 (see Figure 16) which has downwardly extending side flanges 191 provided with outwardly extended feet 192 slidably guided beneath guide strips 193 overlying side guides 194 to which the strips 193 are secured. The forward end of the slide 190 may be secured as by screws 195 to the rear end of a tool holder slide 15. This tool holder slide 15, as shown in Figure 16, is provided with grooves 201 in its side edges for the reception of guide and retaining strips 202 which are secured as by screws to the faces of the turret 11. Each slide 15 is also provided with a longitudinally extending T slot in its upper face at 205 to facilitate the attachment thereto of a tool holder such as the tool holder 206 of Figure 1 carrying the drill 16.

The disk 185 which is journaled in the casing 189 is angularly adjustable in order to vary the angle of inclination of the slot 184 to the perpendicular to the direction of motion of the slides 190 and 15. To this end the upper portion of the disk 185 may be provided with a worm portion 210 with which meshes a worm 211 carried by a horizontal shaft 212 provided with a knurled head 213 at its outer end by which it may be turned. This shaft 212 is suitably journaled in a portion 214 of the casing 189 and is held in position by a cap 215 secured as by screws 216. By turning the knurled head 213 it will be evident that the disk 185 may be angularly adjusted.

The casing 189 has secured to its upper face a ring 220 having a lateral extension 221 provided with an index mark 222. The disk 185 has a central hub portion 223 which extends through the ring 220 and to the top of this extension is secured as by screws 224, a circular cap 225 having a downwardly tapered flange 226 overlying the ring 220 and provided with index markings cooperating with the mark 222 on the extension 221.

For any given throw of the lever 138, the angular adjustment of the disk 210 determines the

extent of the fast feed produced by the rotation of the cam 130, and the slow feed produced thereafter by the rocking of the lever 138 through the action of a follower 145 on the face cam 144. The effects of this angular adjustment of the disk 210 for one position of an actuating cam follower roll 145 for one of the indexing stations is shown diagrammatically in Figures 34 to 41, inclusive. Figures 34 to 37 show successive positions of the tool moving parts where the disk 185 is turned counterclockwise from the position where the slot 184 lies transverse to the line of motion of the tool slide by a small angle.

This means for adjusting the throw of a tool slide by the angular adjustment of a disk provided with a guideway carrying a slide block which is moved in the direction having components lengthwise of the slide motion and transverse thereto is broadly claimed in my application for United States Letters Patent Serial No. 662,701, filed April 17, 1946, for Tool Slide Actuating Mechanism.

As the lever 138 is rocked with its lower end to the left by the rotation of the cam 130 from the position shown in Figures 34 to 35, the slide 141 is moved from its fully retracted position in Figure 34 to the position in Figure 35 where the cam face 144 of the slide 141 contacts with one of the follower rolls 145 on the cam drum 146. The follower roll 178 follows the inclined groove 179, and the slide block 183 which engages in the slot 184 travels to the left in the slot 184 of the disk 185, as shown, while the disk itself is being moved forward from the rear end of the slot 179 slightly more than half way. Since the slide block 183 has moved to the right in the slot 184, the distance that the disk 185, and consequently the tool slide, has moved forward, is somewhat less than it would have been had the slot 184 been exactly transverse to the direction of motion of the tool slide. The total forward movement of the tool slide is then represented by the length H, and this represents the length of fast feed of the tool toward the work due to the rotation of the cam 130. The fulcrum 137 of the lever 138 now remains fixed, the cam 130 having now stopped its rotation, and further forward movement of the tool slide is produced by the action of the cam follower 145 against the edge cam 144. The amount of this motion is shown by a comparison of Figure 35 with Figures 36 and 37, Figure 37 showing the completion of the feeding action where the follower roll 145 is on the high point of the cam face 144 and Figure 36 showing an intermediate position. During this motion, the disk 185, and correspondingly the tool slide, has been moved forwardly the distance L shown in Figure 37, this being slightly longer than would have been the case had the slot 184 been arranged transverse to the line of motion since it has now come back to its mid position from its right hand position of Figure 35.

The positions shown in Figures 35 and 37 may now be compared with the positions shown in Figures 38 and 39, in which latter figures the disk 185 has been adjusted with its slot 184 exactly transverse to the line of feed of the tool so that no effect of the slot 184 is produced on the feed which is entirely produced by the amount of forward motion of the follower 178.

It will be noted that the high speed stroke H of Figures 38 and 39 is less than the distance H of Figures 35 to 37 and the low speed travel L is greater than L. If now the disk 185 be turned to slope in the opposite direction than that shown

in Figures 34 and 37, or as shown in Figures 40 and 41, the corresponding extents of high and low speed motion are varied as shown in Figures 40 and 41, the high speed motion H' being less than H in Figures 39 and 35 and the extent of low speed feed L' being greater than L in Figures 37 and 39.

It will be noted, however, that due to the fact that the angular position of the follower 145 when the cam face 144 contacts therewith is adjustable, there is also possible a feed variation due to changes in the angular positions of the cam followers 145. The effect of this is shown for one angular position of the disk 185 in Figure 42 compared with Figures 38 and 39. The cam follower 145 when first contacted by the cam 143 in Figure 42 is much further advanced on its slope toward the high point of the cam than as shown in Figure 38 where the angular position of the disk 185 is the same as in Figure 42. The extent of high and low speed motions of the tool, however, is very different and is seen by a comparison of Figures 42 and 39, the extent of high speed feed H'' being very much greater than H' of Figure 39, and the low speed motion L'' being very much less than the low speed motion L' of Figure 39.

Means are provided by which both these factors of angular position of the disk 185 and the position of the follower roll 145 when the cam face 144 contacts with it, may be correlated in a predetermined manner so that the desired extents of fast idle and slow feed may be adjusted throughout a large range. To this end each of the disks 225 for the angular adjustable members 185 for the several index stations may be provided with distance indications thereon as shown in Figures 17, 21, 24, 27 and 33. These may be arranged, as shown, in a plurality of series arranged at different axial distances from their centers. As shown there are three such series marked I, II, and III, beginning with those nearer to the centers of these disks, and by turning the corresponding adjusting knobs 213, these indicating disks may be turned to bring any selected of these indications opposite to the indication 222 on the index ring 220. Cooperating with the periphery of the drum 146 to which the followers 145 are secured, as shown best in Figures 6, 18, 19, 20, 22, 23, 25, 26, 28 and 29 is a stationary curved indexing strip 300 and on this strip 300 is positioned an arrow at 301 and three other arrows spaced therefrom 302, 303 and 304.

The manner by which these various index markings may be utilized may best be explained by assuming certain desired values of slow feed for tools on the five stations as illustrated in Figures 17 to 33. Assuming that the desired slow working stroke of the tool at the first station is to be 2 of an inch, the indicator disk 225 at this station is turned to bring the figure 200 opposite the index mark 222, as shown in Figure 17. This figure 200 is in the inner column at the index I. The drum 146 is then turned as by reverse rotation of the shaft 42 by hand into an angular position with the arrow 305 opposite to the arrow 301 on the strip 300, a cam follower 145 is positioned opposite to the arrow I on the strip 300 as shown in Figure 19. The drum 146 is then turned backwardly until this follower 145 is brought opposite to the arrow 301 as shown in Figure 20. At the second station it is assumed that the distance desired for the slow feed is 4.5 and the disk 225 for station 2 is adjusted to bring the mark 4.5 opposite to the index 222 as shown in Figure 21. It will be noted

that this distance 4.5 is in the row marked III. Another follower roll 145-2 is then secured to the drum 146 opposite the arrow 304 as shown in Figure 22, this being the position for the second station. The drum 146 is then turned backwardly until the roll 145-2 for the second station is opposite to the arrow 301 as shown in Figure 23. Assuming that for the third station a slow feed of 1.2 inches is desired, its disk 225 (Figure 24) is turned to present 1.2 opposite to the index mark 222 and it will be noted that this distance 1.2 is in the row II. With the follower roll for the second station still opposite to the arrow 301, a follower roll 145-3 for station 3 is fixed opposite to the index mark 303 as shown in Figure 25, and the drum 146 is then turned backwardly until this follower 145-3 for the third station is opposite to the arrow 301.

Assuming that at the fourth station a slow feed of 2.7 inches is desired, the disk 225 for the fourth station (Figure 27) is turned to bring the indication 2.7 opposite to the index point 222 and with the follower 145 for the third station still opposite to the arrow 301. Another follower 145-4 for the fourth station is fixed opposite to the arrow 304 corresponding to the III column where the distance 2.7 occurs, this being as shown in Figure 28. The cam drum 146 is then further moved backwardly until the cam roll 145-4 for the fourth station is opposite to the arrow 301, as shown in Figure 29. Assuming at the fifth station the slow feed desired is .6, the disk 225 at the fifth station (Figure 30) is turned to bring this distance opposite to the index 222 and while the cam roll 145-4 for the fourth station is opposite to the arrow 301, the fifth follower roll 145-5 is positioned opposite to the arrow 302 corresponding to the I row in which the distance .6 is found on the fifth station disk 225. The five cam follower rolls 145 are now arranged so that when the machine is in operation, the slow feed of the tools at the several stations will correspond with the desired distances.

The positions of these cam rolls 145 having thus been determined, the angular positions of the lobes 73 for the various stations are so adjusted that the indexing is started at the completion of the slow feed of each, and the rings 74 are then fixed in adjusted positions.

Figure 33 shows the positions of the five follower rolls 145 in a development of the cam drum 146. So long as any of these cam followers 145 are in operative relation, the cam drum 146 is being turned at its low working speed. It is turned at its fast speed for the operation of stock feeding and other mechanisms for which fast rotation is desirable during the remainder of its angular extent, such fast speed being as shown, for example, in my Patent No. 2,506,515, to which reference has already been made, but as the mechanisms for producing these other functions form no part of the present invention they are not further disclosed herein.

From the foregoing description of an embodiment of this invention, it should be evident to those skilled in the art that various changes and modifications might be made without departing from its spirit or scope.

I claim:

1. A machine of the class described, comprising a rotary work-carrying spindle, an indexing tool-carrying turret provided with a plurality of tool supports at different angular positions arranged for successive presentation into an operative index position with relation to work carried

5 by said spindle, means for indexing said turret, means for starting said indexing means, mechanism movable with said turret for stopping the indexing means when the corresponding index station has been reached and said indexing mechanism has completed its cycle of operations, means for locking said turret in indexed position, and means actuated by said indexing means for actuating said locking means to unlock said turret in advance of each indexing.

2. A machine of the class described, comprising a rotary work-carrying spindle, an indexing tool-carrying turret provided with a plurality of tool supports at different angular positions arranged for successive presentation into an operative index position with relation to work carried by said spindle, means for indexing said turret, means for starting said indexing means, mechanism independent for each index position for stopping the indexing means when the corresponding index station has been reached and said indexing mechanism has completed its cycle of operations, means for locking said turret in indexed position, and means actuated by said indexing means for actuating said locking means to unlock said turret in advance of each indexing.

3. A machine of the class described, comprising a rotary work-carrying spindle, an indexing tool-carrying turret provided with a plurality of tool supports at different angular positions arranged for successive presentation into an operative index position with relation to work carried by said spindle, means for indexing said turret, means for starting said indexing means, mechanism movable with said turret for stopping the indexing means when the corresponding index station has been reached and said indexing mechanism has completed its cycle of operations, said mechanism having means actuatable to render inoperative said indexing stopping means thereby to permit indexing to continue to a succeeding station, means for locking said turret in indexed position, and means actuated by said indexing means for actuating said locking means to unlock said turret in advance of each indexing.

4. A machine of the class described, comprising a rotary work-carrying spindle, an indexing tool-carrying turret provided with a plurality of tool supports at different angular positions arranged for successive presentation into an operative index position with relation to work carried by said spindle, means for indexing said turret, means for starting said indexing means, mechanism independent for each index position for stopping the indexing means when the corresponding index station has been reached and said indexing mechanism has completed its cycle of operations, said mechanism having means actuatable to render inoperative said indexing stopping means thereby to permit indexing to continue to a succeeding station, means for locking said turret in indexed position, and means actuated by said indexing means for actuating said locking means to unlock said turret in advance of each indexing.

5. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said

shaft, and means driven by said shaft for controlling said connecting and disconnecting means including mechanism individual to each index position successively interposed in said means, each of said mechanisms including a member movable between an operative position and an inoperative position in which its mechanism is inoperative to disconnect said indexing means from said rotary shaft to thereby cause the indexing action to continue to a subsequent station.

6. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said shaft, and means driven by said shaft for controlling said connecting and disconnecting means including mechanism individual to each index position successively interposed in said means, each of said mechanisms including a member rockably mounted and adjustable between two angular positions one of which is an operative position and the other of which is an inoperative position in which its mechanism is inoperative to disconnect said indexing means from said rotary shaft to thereby cause the indexing action to continue to a subsequent station.

7. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said shaft, means driven by said shaft for controlling said connecting and disconnecting means including mechanism individual to each index position successively interposed in said means, each of said mechanisms including a member movable between an operative position and an inoperative position in which its mechanism is inoperative to disconnect said indexing means from said rotary shaft to thereby cause the indexing action to continue to a subsequent station, means for locking said turret in indexed position, and means actuated by said indexing means for actuating said locking means to unlock said turret in advance of each indexing.

8. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said shaft, means driven by said shaft for controlling said connecting and disconnecting means including mechanism individual to each index position successively interposed in said means, each of said mechanisms including a member rockably mounted and adjustable between two angular positions one of which is an operative position and the other of which is an inoperative position in which its mechanism is inoperative to disconnect said indexing means from said rotary shaft to thereby cause the indexing action to continue to a subsequent station, means for locking said

turret in indexed position, and means actuated by said indexing means for actuating said locking means to unlock said turret in advance of each indexing.

5. 9. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said shaft, means driven by said shaft for controlling said connecting and disconnecting means including a rock shaft, for each station carried to be indexed with said turret for successive interposition in said control means, means normally biasing each of said rock shafts to one angular position, means individual for each indexed position for rocking the rock shaft then interposed from said biased position to actuate said connecting and disconnecting means to connect said indexing means to index said turret, and means holding said connecting and disconnecting means in connected position until the completion of an indexing action and the interposition of a succeeding rock shaft into said connecting and disconnecting means and to then cause said succeeding rock shaft to disconnect said indexing mechanism.

10. A machine of the class described, comprising a rotary work spindle, an indexing tool-carrying turret provided with a plurality of tool supports at different angular positions arranged for successive presentation into an operative index position of said turret with relation to work on said spindle, means for indexing said turret, a rotary shaft, means for operatively connecting and disconnecting said indexing means and said shaft, means driven by said shaft for controlling said connecting and disconnecting means including a rock shaft for each station carried to be indexed with said turret for successive interposition in said control means, means normally biasing each of said rock shafts to either of two positions, means individual for each indexed position for rocking the rock shaft then interposed from one of said biased positions to actuate said connecting and disconnecting means to connect said indexing means to index said turret, means holding said connecting and disconnecting means in connected position until the completion of an indexing action and the interposition of a succeeding rock shaft into said connecting and disconnecting means and to then cause said succeeding rock shaft to disconnect said indexing mechanism, and means for rocking each of said rock shafts to the other angular position to which it is biased by said biasing means ineffective to disconnect said indexing means whereby said indexing means continues to operate.

11. A machine of the class described, comprising a rotary work spindle, an indexing tool-carrying turret mounted on an axis substantially parallel to that of said spindle and carrying a plurality of tools at different angular positions brought successively into operative relation to work on said spindle by indexing motion of said turret, a rotary control shaft, means for rotating said control shaft, a jack shaft, an indexing Geneva arm carried by said jack shaft, a Geneva wheel rotatable with said turret and with which said Geneva arm cooperates to index said turret, a rock shaft carried by said turret for each in-

15

dexed position, a drum coaxial with said jack shaft and rotated from said control shaft, lugs carried by said drum in different axial positions therealong, one of said lugs corresponding to each indexed position, the turret rock shaft for the corresponding index position having a dog lying in the plane of motion of said lug, means including a clutch for driving said jack shaft when said clutch is closed, a brake for said jack shaft for stopping its rotation, means actuatable to open said brake and close said clutch or to open said clutch and apply said brake, a cam movable with said indexing arm and engaging said actuatable means to hold said clutch closed while said arm is indexing until said arm has completed a complete indexing revolution, means for operating the operative rock shaft then in position to actuate said actuatable means to open said clutch and stop the rotation of said jack shaft when said cam reaches a fully indexed position, and means actuatable to turn any selected rock shaft with its dog into inoperative position to permit said indexing arm to be rotated through a succeeding indexing rotation without being stopped.

12. In combination, a rotary work spindle, a tool carrier, a rotary shaft, a member carried by said shaft spaced from its axis, a member mounted for motion parallel to the axis of said shaft, one of said members being a cam and the other of said members being a follower for said cam, means actuatable to move said second mentioned member toward said shaft-carried member to a predetermined position relative thereto, whereby said second mentioned member may be forced from said shaft-carried member by the rotation of said shaft, means causing said forced motion of said second mentioned member to move said tool carrier toward work carried by said spindle, and means for returning said second mentioned member to starting position and to withdraw said tool carrier, the timing of the angular position of said shaft and the movement of said second mentioned member being adjustable to thereby determine the extent of cam face engaged by said follower and effective to move said tool carrier toward the work, and means for producing such adjustment.

13. In combination, a rotary work spindle, a tool carrier, a rotary shaft, a member carried by said shaft spaced from its axis, a member mounted for motion parallel to the axis of said shaft, one of said members being a cam and the other of said members being a follower for said cam, means actuatable to move said second mentioned member toward said shaft-carried member to a predetermined position relative thereto, whereby said second mentioned member may be forced from said shaft-carried member by the rotation of said shaft, means causing said forced motion of said second mentioned member to move said tool carrier toward work carried by said spindle, and means for returning said second mentioned member to starting position and to withdraw said tool carrier, said shaft-carried member being securable to said shaft in any of a plurality of positions angularly spaced about the axis of said shaft to thereby selectively determine the extent of cam face engaged by said follower and effective to move said tool carrier toward the work.

14. In combination, a rotary work spindle, a tool carrier, a rotary shaft, a cam follower carried by said shaft spaced from its axis, an edge cam mounted for motion parallel to the axis of said shaft, means actuatable to move said cam toward said follower to a predetermined position relative

to said follower where said follower may engage said cam face and force said edge cam in the opposite direction, means effective to cause said forced motion of said cam to move said tool carrier toward work carried by said spindle, means for returning said cam to starting position and for withdrawing said tool carrier, the timing of the angular position of said shaft and the movement of said cam to said predetermined position being adjustable to thereby determine the extent of cam face engaged by said follower and effective to move said tool carrier toward the work, and means for producing such adjustment.

15. In combination, a rotary work spindle, a tool carrier, a rotary shaft, a cam follower carried by said shaft spaced from its axis, an edge cam mounted for motion parallel to the axis of said shaft, means actuatable to move said cam toward said follower to a predetermined position relative to said follower where said follower may engage said cam face and force said edge cam in the opposite direction, means effective to cause said forced motion of said cam to move said tool carrier toward work carried by said spindle, and means for returning said cam to starting position and for withdrawing said tool carrier, said shaft having means for securing said cam follower thereto selectively in any of a plurality of positions spaced angularly about its axis to thereby determine the extent of cam face engaged by said follower and effective to move said tool carrier toward the work.

16. In combination, a rotary work spindle, a tool carrier turret having a plurality of tool carriers arranged in spaced angular relation to be brought successively into operative angular positions by indexing of said turret, a rotary shaft arranged parallel to said work spindle, a drum fixed to said shaft, a cam follower carried by said drum, a segmental edge cam having a cam face with which said follower may engage and mounted for motion parallel to said shaft axis, a stop limiting the extent of withdrawal of said cam away from said drum, a lever having a fulcrum transverse to said axis and mounted for limited motion parallel to said axis, one arm of said lever engaging said cam to be moved by said cam and another arm in operative relation to that tool carrier in operative angular position at any time, means for rotating said shaft once for each index position of said turret, means for moving said fulcrum to a forward position to bring said cam away from said stop into position to be contacted by said follower during a portion of the rotation of said shaft for said lever to be rocked in direction to feed that tool carrier in operative angular position toward the work, and to move said fulcrum to a rearward position to retract said cam against said stop and to retract said tool carrier, and means to index said turret while said tool carrier is retracted, said fulcrum moving means having control mechanism independently adjustable for each indexed position of said turret and determining the angular position of said shaft at which said forward motion of said fulcrum begins.

17. In combination, a rotary work spindle, a tool carrier turret having a plurality of tool carriers arranged in spaced angular relation to be brought successively into operative angular positions by indexing of said turret, a rotary shaft arranged parallel to said work spindle, a drum fixed to said shaft, a cam follower carried by said drum, a segmental edge cam having a cam face with which said follower may engage and mount-

ed for motion parallel to said shaft axis, a stop limiting the extent of withdrawal of said cam away from said drum, a lever having a fulcrum transverse to said axis and mounted for limited motion parallel to said axis, one arm of said lever engaging said cam to be moved by said cam and another arm in operative relation to that tool carrier in operative angular position at any time, means for rotating said shaft once for each index position of said turret, means for moving said fulcrum to a forward position to bring said cam away from said stop into position to be contacted by said follower during a portion of the rotation of said shaft for said lever to be rocked in direction to feed that tool carrier in operative angular position toward the work, and to move said fulcrum to a rearward position to retract said cam against said stop and to retract said tool carrier, and means to index said turret while said tool carrier is retracted, said fulcrum moving means having control mechanism independently adjustable for each indexed position of said turret and determining the angular position of said shaft at which said forward motion of said fulcrum begins, and said drum having a plurality of angular positions at which said follower may be selectively positioned.

18. In combination, a rotary work spindle, a tool carrier turret having a plurality of tool carriers arranged in spaced angular relation to be brought successively into operative angular positions by indexing of said turret, a rotary shaft arranged parallel to said work spindle, a drum fixed to said shaft, a cam follower carried by said drum, a segmental edge cam having a cam face with which said follower may engage and mounted for motion parallel to said shaft axis, a stop limiting the extent of withdrawal of said cam away from said drum, a lever having a fulcrum transverse to said axis and mounted for limited motion parallel to said axis, one arm of said lever engaging said cam to be moved by said cam and another arm in operative relation to that tool carrier in operative angular position at any time, means for rotating said shaft once for each index position of said turret, means for moving said fulcrum to a forward position to bring said cam away from said stop into position to be contacted by said follower during a portion of the rotation of said shaft, for said lever to be rocked in direction to feed that tool carrier in operative angular position toward the work, and to move said fulcrum to a rearward position to retract said cam against said stop and to retract said tool carrier, and means to index said turret while said tool carrier is retracted, said fulcrum moving means having control mechanism independently adjustable for each indexed position of said turret and determining the angular position of said shaft at which said forward motion of said fulcrum begins, said drum having a plurality of angular positions at which said follower may be selectively positioned, and means for limiting the forward motion of said cam when said follower is not in cam-contacting position when such forward motion of said cam occurs.

19. A machine of the class described, comprising a rotary work spindle, an indexing tool-carrying turret having its indexing axis arranged parallel with said spindle, a plurality of tool carriers arranged in spaced angular relation on said turret to be brought successively into operative angular relation to work on said spindle by

indexing of said turret, means for moving that tool carrier in operative angular relation at any one time toward and from the work, and mechanism for rocking said turret about its indexing axis when a tool carried by said tool carrier is in engagement with the work.

20. A machine of the class described, comprising a rotary work spindle, an indexing tool-carrying turret having its indexing axis arranged parallel with said spindle, a plurality of tool carriers arranged in spaced angular relation on said turret to be brought successively into operative angular relation to work on said spindle by indexing of said turret, means for moving that tool carrier in operative angular relation at any one time toward and from the work, means for locking the turret in indexed angular position, means movably supporting said locking means, and means actuatable to move said locking means while a tool is in engagement with the work to rock said turret about its indexing axis.

21. A machine of the class described, comprising a rotary spindle, an indexing tool-carrying turret having a plurality of tool carriers in spaced angular relation about the indexing axis of said turret to be brought into operative relation to work on said spindle by indexing of said turret, means for indexing said turret, means for locking said turret in indexed position comprising a locking element, means for supporting said element for turret locking and releasing motion and for motion transverse to said locking and releasing motions, and means actuatable to move said element in said transverse direction while it is in turret-locking position to thereby rock said turret while a tool carried thereby is in engagement with the work.

22. A machine of the class described, comprising a rotary spindle, an indexing tool-carrying turret having a plurality of tool carriers in spaced angular relation about the indexing axis of said turret to be brought into operative relation to work on said spindle by indexing of said turret, means for indexing said turret, means for locking said turret in indexed position comprising a lever having a locking finger for engagement in any of a plurality of recesses angularly positioned with respect to said turret, means for rocking said lever into and out of locking position, a movable mounting for the fulcrum of said lever, and means actuatable to move said fulcrum while a tool is in engagement with the work and while said finger is in one of said recesses to thereby rock said turret about its indexing axis.
